UNITED STATES PATENT OFFICE.

CALVIN B. STEFFENS, OF ALLENTOWN, MISSOURI.

AUXILIARY FORD STARTER SWITCH AND SWITCH-OPERATING MECHANISM.

Application filed August 12, 1926. Serial No. 128,718.

This invention relates to auxiliary Ford starter switches and switch-operating mechanisms and has as its prime object the provision of a device of this kind to permit the chauffeur to assist the starter in turning over the engine by cranking the same while operating the starter switch.

Another object is to provide a device of this kind which is adapted to fit the later model Fords and primarily intended for use in cold weather.

A further object is to construct a simple and practical device of the kind described which is adapted to cooperate with the primary starter switch.

A still further object is to provide a compact and substantial switch which can be operated from the front of the machine.

Other objects and advantages of the device will be apparent from the accompanying drawings and specification.

In the drawings—

Figure 1 is a plan view of a Ford chassis and engine having this invention mounted thereon; the chassis and engine being shown in dotted lines.

Figure 2 is a cross section of the chassis taken on the line 2—2 of Figure 1.

Figure 3 is a plan view of the switch as connected with the starter switch; the switch being shown in dotted lines.

Figure 4 is a plan view of the switch independent of the starter switch with the cover removed.

Figure 5 is a side elevation of the switch as shown in Figure 4.

Figure 6 is a transverse section of the switch taken on the line 6—6 of Figure 3.

Figure 7 is a detail of the switch base and terminal posts.

Figure 8 is a detail of the contact plate and associated levers.

Figure 9 is a plan view of the auxiliary bracket and lever.

Figure 10 is a side elevation of the said auxiliary bracket and lever.

In carrying out this invention I provide a base 1 formed with a bracket 2 and an integral side 3. Terminals 4 are insulated against and passed thru the said side 3 and are connected by means of conductors 5 with the conventional terminals 6 of the late model Ford starter switch 7. A pivot pin 8 is rigidly secured in the base 1 and has a bracket 9 carrying a coil spring 10 mounted thereon. The said bracket 9 is prefer-

ably formed from flat sheet metal provided with ears 11 pierced with apertures 12 thru which the pin 8 passes. The lower ear 11 is formed with an integral lever 13. The coil spring 10 has its one end 14 secured in the base 1 and its opposite end 15 in the upper ear 11 of the bracket 9. The forward end 16 of the said bracket 9 carries a conductor bar 17 which is adapted to engage the terminals 4 for closing the electric circuit thru said terminals 4. The said conductor bar 17 is insulated against the bracket 9 to prevent all possibilities of short circuiting thru the said bracket 9. A cover 18 is provided with an integral arm 19 thru which a screw 20 is passed to permit securing the said cover to the base 1. A screw 21 is also passed thru the cover 18 and is adapted to be screwed into the pivot pin 8. A slot 22 is cut in the cover 18 in order to give free action to the lever 13. The bracket 2 is to be secured underneath the floor boards of the machine for which the device is adapted adjacent the starter switch 7. The switch as shown is intended primarily to permit closing the electric circuit thru the starter 23 of the engine 24 from the front of the machine. For this purpose it is necessary to provide a special bracket 26 which is secured to the automobile chassis 25. A lever 27 is pivotally secured to the bracket 26. The said lever 27 is substantially triangular in form and is pivoted thru the base of said triangular formation to the said bracket 26 as described. The forward end of the lever 27 has a pole wire 28 secured thereto. The said wire 28 passes thru the bottom of the radiator shell (not shown) and is formed at its free end with a finger loop 29. The base of the said lever 27 adjacent the pivot point of said lever is pierced with an aperture 30 to permit securing a tie-wire 31 therein which is secured in the lever 13.

The switch as described is intended primarily for use upon the later model Fords in conjunction with the starter switch 7. In extremely cold weather, when the engine is stiff so as to overload the starter 23, it is desirable at times to assist the said starter by cranking while the starter is endeavoring to turn over the crankshaft (not shown) of the engine. In this respect it is necessary to close the circuit thru the starter switch 7.

In operation the starter switch 7 is closed by drawing out the pole wire 28 which

2
partially rotates the lever 27 on its pivot thereby drawing the lever 13 toward itself thru the medium of the wire 31. In thus drawing the lever 13 toward the lever 27 the bracket 9 is turned upon its pivot 8 so that the conductor bar 17 will engage the terminals 4 and thus close the electric circuit thru said terminals. As soon as the wire 28 is released the spring 10 turns the bracket 9 to its former position thus breaking the electric circuit thru the said terminals 4.

While I have herein described a certain specific method of constructing and assembling the elements of my invention, it is understood same may be varied in minor details, not departing from the spirit of my invention as defined in the appended claims.

I claim:

20 1. In a switch of the kind described in combination with a conventional form of starter switch embodying conductors connected to the starter switch terminals; a base formed with an integral side and a bracket for securing to the underside of the starter switch; insulated terminals passed

thru said side connected to said conductors; a spring set bracket formed with a lever pivoted on said base; an insulated conductor bar secured to said bracket for engaging 30 said terminals passed thru said side; a bracket secured to the chassis of the machine; a triangular lever pivoted on said bracket; a wire secured to said bracket; a wire secured to said bracket lever and said triangular lever; and means secured to said triangular lever extending at the front of the car for operating said switch.

2. In a device of the kind described adapted for use in connection with a late model 40 starter switch embodying conductors mounted on the starter switch terminals; a base formed with a bracket for securing to said starter switch; terminals connected with said conductors mounted on said base; an insulated conductor bar pivotally mounted on said base for engaging the terminals mounted on said base; and flexible means connected to said conductor bar for operating the switch from the front of the machine. 50

In testimony whereof I affix my signature.

CALVIN B. STEFFENS.
